INGOT MOLD CLEANING DEVICE AND BRUSH

Theodore A. Repper and Joseph J. Spang,
Middletown, Ohio

Application January 19, 1950, Serial No. 139,388

2 Claims. (Cl. 15—164)

1

This invention relates to an ingot mold cleaning device and brush. In the casting of iron or steel ingots or the like it is necessary, after an ingot has been stripped from the mold, to scrub the inside of the mold to remove accumulated scale and dirt so as to prepare the mold for a succeeding casting operation. The cleaning of an ingot mold has always presented a difficult problem for the reason that the ingot mold is very large and cumbersome and the inside surfaces thereof are difficult to get at.

It is an object of the present invention to provide a device which will greatly simplify the operation of cleaning an ingot mold after a casting operation. It is another object of our invention to provide a device as outlined above which can be handled with an overhead crane. We rely upon the weight of the device to lower it into the ingot mold and we use an overhead crane or the like to withdraw it from the mold. The cleaning operation is carried out during the in and out movement of the device with respect to the mold.

It is another object of our invention to provide a replaceable brush for the device so as when a brush member becomes worn it may be easily replaced. In connection with this object, it is another object of our invention to provide a new form of brush.

These and various other objects of our invention which we shall point out in detail herein-after or which will become apparent to one skilled in the art upon reading these specifications we accomplish by that certain construction and arrangement of parts of which we shall now describe an exemplary embodiment.

Reference is made to the drawings forming a part hereof and in which—

Figure 1 is a fragmentary side elevational view of a device according to our invention with parts broken away and parts in section.

Figure 2 is a cross sectional view taken on the line 2—2 of Figure 1.

Figure 3 is a fragmentary cross sectional view taken on the line 3—3.

Figure 4 is an elevational view of Figure 3.

Figure 5 is a fragmentary perspective view of a supporting member.

Figure 6 is a vertical cross sectional view taken on the line 6—6 of Figure 1.

Figure 7 is a fragmentary elevational view of a brush and brush holder.

Figure 8 is a cross sectional view taken on the line 8—8 of Figure 7.

Figure 9 is a fragmentary cross sectional view taken on the line 9—9 of Figure 7.

Figure 10 is a detailed elevational view of one of the bristle tufts, and Figure 11 is an elevational view of a tuft-holding pin.

Briefly, in the practice of our invention we provide a block of generally rectangular configuration, and we pivot brush-holding members to the sides, ends and corners of the block. The

2

side and end brush holders are preferably in a single horizontal plane, while the corner brush holders are in a common plane preferably above the others. The brush holders are pivotally mounted so that they may swing outwardly away from the block, and spring means are provided to urge them outwardly. The block is provided with a suspension member by means of which it may be handled with an overhead crane or the like, and the suspension member is provided with means for supporting weights which may be added as required to insure the device dropping into an ingot mold by gravity.

The brushes themselves are constituted of perforated plates, and the bristles are made of stranded cable doubled upon itself and twisted to form an eye. Pins passing through a series of eyes hold the tufts in place.

Referring now in more detail to the drawings, the block is indicated generally at 10. The side brushes are indicated at 11, the end brushes at 12 and the corner brushes at 13. It may be pointed out that in Figures 1 to 4 inclusive and 6 the brush holders and brushes have been indicated more or less diagrammatically. The details of the brushes and brush holders are shown in Figures 7 to 11 inclusive. It will, of course, be understood that the brushes 11, 12 and 13 are all made as illustrated in Figures 7 to 11 inclusive.

As best seen in Figure 6, the brush holders for the brushes 11 are mounted on pivoted arms 14 which are pivoted in slots in the block 10 at the points indicated at 15. Each of the arms 14 is provided with an upward extension 16 to which are secured the bolts 17.

Extending upwardly from the block 10 is a suspension member 18 which has at its upper end an eye member 19 for use with the hook of an overhead crane or the like. The bolts 17 previously referred to pass through enlarged apertures 19 in the suspension member 18 and are provided with the nuts 20. Compression springs 21 are disposed about the bolts 17 between the extensions 16 and the suspension member 18. From the foregoing it will be clear that the springs 21 tend to urge the extensions 16 away from the suspension member 18 thus rocking the arms 14 about their pivot point 15 and thrusting the brush members 11 outwardly. The nuts 20 limit the outward movement of the brushes. The brush holders are secured to the arms 14 by nuts and bolts as indicated at 22.

The end brushes 12 are mounted in the same way as described above. Thus there are provided the pivoted arms 23 (see Figure 1) having the upward extensions 24 to which are secured the bolts 25 having the nuts 26 and springs 27. Again the brush holders 12 are secured to the arms 23 by nuts and bolts as indicated generally at 27. In the case of the end brushes however the bolts 25 do not pass through the suspen-

sion member 18. Instead there is secured to the block 10 a supporting plate 28. (See in perspective in Figure 5.) The plate 28 has an elongated aperture 29 for the passage of the bolt 26. The plate 28 is secured to the block 10 by means of machine screws 30. Thus the outward thrust 5 upon the brushes 12 is produced by the compression springs bearing between the extensions 24 and the supporting members 28.

The members 28 have angularly related edge portions 28a which are used as will be described hereinafter in connection with the corner brush members.

As best seen in Figures 3 and 4, the corner brush members are generally similar to the side and end brush members in that there are arms 31 which are pivoted as at 32 to the block 33 which in turn are secured by bolts or the like to the block 10. In the particular embodiment shown the arms 31 are welded as at 31a to the links 34 which in turn are pivoted on the pins 35. The corner brushes are not provided with upward extensions but instead the studs 36 are bolted to the portions 28a mentioned above and other studs 37 are secured to the arms 31. The studs 36 and 37 are aligned axially and springs 38 tend to urge the brush members 13 away from the portions 28, similarly to the arrangement described above in connection with the side and end brushes.

The brushes 13 at the corners are preferably mounted above the side and end brushes so that there is overlap between the side, end and corner brushes for the purpose of securing continuous cleaning all the way around the internal periphery of the mold.

The suspension member 18 is preferably provided with a supporting block 39 which may be welded thereto as at 40 and which serves to support weights 41 which may be added as required to insure that the device will drop into the ingot mold by virtue of gravity alone.

Coming now to a detailed description of the brushes themselves, reference is had to Figures 7 to 11 inclusive. Each brush comprises a perforated plate 42 in which the perforations are preferably in parallel rows and evenly spaced. The perforations are indicated at 43. These perforations are preferably chamfered on both sides as indicated at 44 and 45. Parallel grooves 46 connect the perforations 43 as shown.

The tufts of bristles are preferably made of lengths of stranded cable which are bent upon themselves and given one or two twists as best seen in Figure 10, whereby the cut ends of the lengths of stranded cable face outwardly and form the individual bristles indicated at 47 in Figure 10. Thus the other end of the tuft is provided with an eye 48. The bristle tufts are placed in the perforations with the eyes 48 lying in the chamfers on the rear side of the plate 42 and pins 49 are then passed along the grooves 46 through the eyes 48 of the bristles in a row, as best seen in Figure 8. As the device is used the bristles tend to fan out as illustrated in Figures 7, 8 and 9.

From the foregoing it will be clear that individual tufts may readily be replaced by withdrawing the appropriate pin 49 and replacing a worn out tuft with a new one, prepared as in Figure 10.

The entire plate 42 with the tufts in position is then placed in a brush holder 50 which may comprise a channel-shaped member of a size to ac-

commodate the plate 42 and the plate 42 is held to the holder 50 by means of the machine bolts 51 and nuts 52. In this manner an entire brush may readily be replaced, if all of the tufts have worn down uniformly.

In use a suitable number of weights 41 are disposed upon the support 49 as shown in Figure 6, and the entire device is lifted up by the eye 19 by the use of an overhead crane or the like, and the cleaning device is then lowered into an ingot mold. In entering the ingot mold which is shown in broken lines at 53 in Figures 1, 2 and 6 the brushes are compressed inwardly against the tension of the springs 21, 27 and 38. The entire cleaning device drops down to the bottom of the ingot mold by gravity and is then lifted out by means of an overhead crane. In so doing the bristles thoroughly clean all internal surfaces of the mold.

It will be clear that the operation is accomplished quickly and efficiently and that not only individual bristle tufts but individual brushes can be replaced as required with a minimum of expense and effort.

It will be clear that numerous modifications may be made without departing from the spirit of our invention, and we therefore do not intend to limit ourselves in any manner except as set forth in the claims which follow.

Having now fully described our invention, what we claim as new and desire to secure by Letters Patent is:

1. An ingot mold cleaning device comprising a block of generally rectangular shape, brush holders hingedly disposed adjacent the bottom of said block on all four sides thereof substantially in a common plane for pivotal movement with respect to said block, other brush holders hingedly disposed at the four corners of said block in a different plane, spring means for urging said brush holders to pivot away from said block, and means for limiting the outward movement of said brush holders, and brushes mounted in said brush holders, the brushes in the first mentioned brush holders extending substantially the full length of the four sides of said block, and the brushes in said other brush holders circumferentially overlapping the brushes at the respective adjacent sides.

2. A device according to claim 1, wherein said block is provided with a rigid suspension member whereby it may be suspended from an overhead crane for handling, said suspension member having a platform above said block to support weights thereon to insure that said device will descend into an ingot mold by gravity.

THEODORE A. REPPER.
JOSEPH J. SPANG.
